Patented Dec. 31, 1912.

UNITED STATES PATENT OFFICE.

GEORGE F. BURMEISTER, OF LORAIN, OHIO.

SHEET-MUSIC TURNER.

1,049,047.

Specification of Letters Patent. Patented Dec. 31, 1912.

Application filed May 21, 1909. Serial No. 497,504.

To all whom it may concern:

Be it known that I, GEORGE F. BURMEISTER, a citizen of the United States, and resident of Lorain, in the county of Lorain 5 and State of Ohio, have invented certain new and useful Improvements in Sheet-Music Turners, of which I hereby declare the following to be a full, clear, and exact description, such as will enable others skilled in the art to which it appertains to 10 make and use the same.

The objects of the invention are to provide a simple and efficient device enabling the performer upon the piano or other musical instrument to turn the music leaves without taking his attention from his work and without losing a beat in his performance.

The invention consists in the use of a pedal operated pneumatic or bulb, in connection with an air propelled reciprocating or oscillating member, and automatically acting leaf turning mechanism automatically connected therewith.

The invention further comprises the combination and arrangement of parts and construction of details as hereinafter described, shown in the accompanying drawings and specifically pointed out in the claims.

In the accompanying drawings, Figure 1 30 is a perspective view of the device, showing the manner of its application to a piano. The bulb and rubber tubing are laid upon the top of the piano case, but in use the bulb lies on the floor where it is accessible to the foot of the player; Fig. 2 is a vertical longitudinal section of the compressed air cylinder showing the connection with the air tube and the piston therein which controls the movements of the leaf turning fingers; Fig. 3 is a horizontal section of this cylinder; Fig. 4 is an end elevation of the cylinder showing the cranked inner extremity of one of the turning fingers; Fig. 5 is a vertical section of the adjustable rear support 40 for the air tube to which the pneumatic cylinder is attached; Fig. 6 is a perspective view of the stop plate and stops thereon.

In these views 1 is a metal air tube which is preferably attached to the piano case or 50 other instrument at the rear, so as not to deface the woodwork. A sliding sleeve 2 is longitudinally adjustable upon the tube 1

by means of a set screw 3. The sleeve 2 is pivoted upon the forked plate 4 and is adjustable therein to place the tube 1 at any 55 desired angle by means of the depending lug 5 and the set screw 6 for a purpose hereinafter more fully described.

7 is the pneumatic cylinder in which moves the piston 8 which is driven outwardly when the bulb 9 is compressed, and returns automatically by the resiliency of the bulb 9 to the end of the cylinder when the bulb expands. To give a quick action the bulb should be reasonably thick and 60 elastic.

10 is the rubber tubing connecting the bulb and metal tube.

The metal tube is the only support for the cylinder 7 and the leaf turning fingers 11, 70 transversely pivoted in the cylinder 7.

The cylinder is set at an angle to the instrument as shown in Fig. 1, and the fingers are vertically pivoted in the cylinder at 12, 12 and extend laterally therefrom. Upon 75 each finger 11 is shown a spring clamp 13, which is loose and slidingly movable thereon. These clamps are provided with two members or plates pivoted together at 14 and one plate is shorter than the other and 80 turned inwardly at 15, so as to clamp the music sheet tightly between the plates. A spring closes them tightly together. By means of manipulation of the set screw 5 the fingers and cylinder can be manually 85 brought to exactly the required position relative to the music rack so as to engage the music leaves readily.

The fingers are operated to swing from the right to the left side of the cylinder and 90 turn the leaves as they are swung by means of the following instrumentalities: Each finger 11 is provided with a vertical portion 16 which is transversely pivoted in the cylinder. The vertical portion is bent at 17' 95 to form a crank. To the piston 8 is attached an arm 18 at the forward extremity of which is pivoted a swinging arm, having a notched or engaging extremity 19 which when the piston moves forward strikes 100 against the several cranks in turn, and as each crank is struck its respective arm is swung through approximately an angle of 180° so as to turn one music leaf over. The

arm will then be in the position shown in Fig. 3. As the piston 8 and arm 18 move backward when the bulb recovers its shape so as to draw the piston the arm strikes against the rigid bar or member 20 and is straightened again as shown in dotted lines in the same figure. As soon as the piston moves forward again, the arm 18 strikes against a second crank and swings a second finger into place. The arm 18 is guided by means of a screw S, moving a slot T in the cylinder wall. See Fig. 3.

In use all the fingers 11, 11 are first turned upon the right of the cylinder and the clamps 13, 13 are attached to the music leaves in regular order. As soon as the bulb is squeezed or flattened the piston moves forward and the arm 18 swings the first leaf and returns in line with the cranks ready to move another finger when the bulb is again pressed. This action is continued until all the leaves are turned.

There is no limit to the number of fingers that can be used and the device can be attached to a music rack of any character. The sliding movement of each clamp upon its finger enables it to adapt itself to each position of the leaf which it is turning without bending the leaf. The cranked wire permits of free movement of the arm in swinging it to place.

To prevent the fingers from striking against the instrument or music rack at each limit of their movement, a small plate 30 is inserted in the cylinder and provided with raised lugs or stops 31 against which the cranks strike in turn at the proper place. These stops are shown inclined to give the proper sweep to the fingers. For convenience in structure the stops 31 and plate 30 and rigid bar 20 are formed of one integral piece of metal and the vertical parts of the fingers can pass through this plate.

Having described the invention what I claim as new and desire to secure by Letters Patent is:—

1. In combination, a pneumatic cylinder, a piston reciprocable therein, a series of fingers pivoted in said cylinder beyond the limit of travel of the piston and having each a cranked portion in line with said piston, the outer ends of said fingers adapted to swing laterally outside of said cylinder, a swinging arm pivotally connected with said piston and reciprocable therewith, and adapted to engage the said cranked portions of said fingers in succession, as said piston moves forward, a pneumatic device for reciprocating said piston and arm, and means for restoring said arm to alinement with the unmoved cranked portions in turn as said arm retires, and a leaf clamping device slidably movable on each arm.

2. In combination, a pneumatic cylinder, a piston reciprocable therein, fingers pivoted

in a longitudinal line in said cylinder for rotary movement, cranks on said fingers, a bar attached to the front end of said piston, a pivoted arm on said bar, said pivoted arm adapted to engage said crank in turn to swing said fingers, and a rigid member in said cylinder, said arm being in position to engage said rigid member on the return movement of the said piston and to be returned into alinement with said cranks thereby, and a pneumatic bulb and pipe communicating with said cylinder behind said piston for operating the same, the said bulb serving also to return said piston.

3. In combination, a music leaf turning device, a pneumatic cylinder, a metal air tube and pneumatic bulb communicating therewith, a series of fingers pivoted in line within said cylinder and capable of lateral movement thereon, a series of cranks in said cylinder on said fingers, a piston in said cylinder reciprocated by said bulb when said bulb is alternately compressed and released, a pivoted device upon said piston adapted to engage said cranks and rotate said fingers in turn when said piston advances, said fingers manually returned, a rigid member in said cylinder in position to engage said pivoted device on the return movement of said piston whereby the pivoted device is returned into line with the series of cranks.

4. In combination in a music leaf turner, a pneumatic cylinder, a series of leaf turning fingers pivoted in a longitudinal line in said cylinder, a series of cranks in said cylinders, each crank connecting operatively with a corresponding finger, a piston in said cylinder, a bulb and connecting tube communicating with said cylinder and adapted to reciprocate said piston, a bar extending outwardly from said piston into said extended portion of said cylinder, said cylinder provided with a guiding slot therefor, an arm pivoted on said bar and adapted to engage each crank in turn, as said piston advances whereby said fingers are severally turned on their pivots, a rigid member in said cylinder being in position to be engaged by said pivoted arm on the return movement of the piston and restore the pivoted arm into line with said series of cranks.

5. In combination in a music leaf turner, a cylinder, a piston reciprocable therein, a bar secured to the forward end of said piston, a pivoted crank operating device on said bar, a series of fingers transversely pivoted in said cylinder, said fingers being manually placed in position, cranks in said cylinder integral with said fingers, said cranks being in position to be engaged in turn by said crank operating device and to be turned thereby as the piston advances, a rigid device adapted to engage said crank

operating device to restore it to its normal position on the return of said piston, stop lugs in said cylinder adapted to limit the movements of said fingers, in each direction, and a guide for said bar in the wall of said cylinder, and means for reciprocating said piston in said cylinder.

In testimony whereof, I hereunto set my hand this 17th day of May, 1909.

GEORGE F. BURMEISTER.

In presence of—

GEO. S. COLE,
Wm. M. MONROE.
